UNITED STATES PATENT OFFICE.

CORWILL JACKSON, OF KALAMAZOO, MICHIGAN.

PNEUMATIC DRILL.

1,376,545.

Specification of Letters Patent.

Patented May 3, 1921.

Application filed June 11, 1919. Serial No. 303,352.

To all whom it may concern:

Be it known that I, CORWILL JACKSON, a citizen of the United States, residing at Kalamazoo, Michigan, have invented certain new and useful Improvements in Pneumatic Drills, of which the following is a specification.

This invention relates to improvements in pneumatic drills.

10 The main objects of this invention are to provide an improved drill which is simple and economical in its parts, light in weight and compact and durable in structure.

15 Further objects, and objects relating to structural details, will definitely appear from the detailed description to follow.

I accomplish the objects of my invention by the devices and means described in the 20 following specification. The invention is clearly defined and pointed out in the claims.

A structure which is a preferred embodiment of my invention is clearly illustrated in the accompanying drawing, forming a 25 part of this specification, in which:

Figure I is a side view of my improved drill.

Fig. II is a detail view mainly in vertical central section.

30 Fig. III is a detail horizontal section on a line corresponding to line 3—3 of Figs. I and II.

Fig. III^A is a detail vertical section on a line corresponding to line 3^A—3^A of Fig. 35 III, showing details of the rotor and its cylinder, and passages and ports thereof.

Fig. IV is an enlarged detail side elevation showing outlet port, the inlet port being indicated by dotted lines.

40 Fig. V is a detail section on a line corresponding to line 5—5 of Fig. II.

In the drawing, similar reference characters refer to similar parts throughout the several views, and the sectional views are 45 taken looking in the direction of the little arrows at the ends of the section lines.

Referring to the drawing, I provide a frame or body comprising a top body member 1, having a handle or grip 2 at the top 50 thereof. On its under side, the body member 1 has a recess-like rotor cylinder 3

formed therein. The inlet passage 4 has an annular delivery portion 5 communicating with the cylinder through a plurality of ports.

55 The intermediate body member 7 constitutes a head or end member for the cylinder and is provided with a chamber-like gear box 8 opening downwardly. The bottom member 9 closes this gear box. The 60 top and intermediate members are secured together by bolts 10, and the bottom member is secured to the intermediate member by screws 11.

Within the rotor chamber, or cylinder, is 65 a rotor 12 having upwardly facing pockets 13 disposed to receive the impact from the propelling fluid such as compressed air. The rotor shaft 14 is supported by a bearing 15 on body member 1, and a bearing 16 70 alined therewith on the intermediate body member 7. The bottom member is provided with a bearing 17 for spindle 18. The spindle is provided for a chuck 19 to receive the drill or tool. The spindle 18 is 75 preferably in alinement with rotor shaft 14.

On the end of the spindle within the gear box is a gear 20 which is connected to a pinion 21 on the rotor shaft by means of the transmission gears 22 and 23 on transmission shaft 24. The upper end of this shaft has a bearing at 25 in the intermediate body member, while its lower end has a bearing 26 in the lower body member. This overlapping arrangement of the gears 80 within the gear box permits a very compact arrangement.

The control valve 27 is arranged in a bore-like valve casing 28 formed in the upper body member. The valve is of the plunger type and has an annular groove 29 adapted to be brought into register with the passage 4. The valve stem 30 is arranged through the body member 1 to project at the top thereof, so that it may be manipulated by the thumb of the operator while grasping the handle 2. The coil spring 31 holds the valve normally closed. The exhaust 32 opens at the side of the body member 1.

100 My improved drill is very compact and durable in structure and convenient to ma-

nipulate. The parts are simple and economical to produce and easily assembled or disassembled, as the occasion requires. The moving parts are all effectively housed and 5 protected.

I have illustrated and described my improvement in an embodiment which I find very practical. I have not attempted to illustrate or describe certain modifications 10 which I contemplate as I believe the disclosure made will enable those skilled in the art to which my invention relates to embody or adapt the same, as may be desired.

15 Having thus described my invention, what I claim as new and desire to secure by Letters Patent is:

1. The combination of a frame or body comprising a top body member provided 20 with a handle and having a cylinder in its under side and inlet and exhaust passages, said inlet passage being provided with an annular delivery portion above the cylinder communicating with said cylinder through 25 a plurality of ports, an intermediate body member constituting a gear box, a bottom member provided with a spindle bearing, said top and intermediate members having alined rotor shaft bearings alined with said 30 spindle bearing and said intermediate and bottom body members having alined transmission shaft bearings disposed at one side of said rotor shaft and spindle bearings, a valve for said inlet passage provided with 35 a stem projecting above said handle, an upwardly facing fluid impact rotor disposed in said cylinder, a shaft therefor disposed in said rotor shaft bearings and projecting into said gear box, a spindle disposed in said 40 spindle shaft bearing, a transmission shaft disposed in said transmission shaft bearings, and a train of spindle driving gears on said rotor and transmission shafts and spindle.

2. The combination of a frame or body 45 comprising a top body member provided with a handle and having a cylinder in its under side and inlet and exhaust passages, an intermediate body member constituting a gear box, a bottom member provided with 50 a spindle bearing, said top and intermediate members having alined rotor shaft bearings alined with said spindle bearing and said intermediate and bottom body members having alined transmission shaft bearings disposed at one side of said rotor shaft and spindle bearings, a fluid impact rotor disposed in said cylinder, a shaft therefor disposed in said rotor shaft bearings and projecting into said gear box, a spindle disposed 55 in said spindle shaft bearing, a transmission shaft disposed in said transmission shaft bearings, and a train of spindle driving gears on said rotor and transmission shafts and spindle.

60 3. The combination of a frame or body

comprising a top body member provided with a handle and having a cylinder in its under side and inlet and exhaust passages, said inlet passage being provided with an annular delivery portion above the cylinder 70 communicating with said cylinder through a plurality of ports, an intermediate body member constituting a gear box, a bottom member, a valve for said inlet passage provided with a stem projecting above said handle, an upwardly facing fluid impact rotor disposed in said cylinder, a rotor shaft projecting into said gear box, a spindle mounted on said bottom member, and a train of spindle driving gears connecting said 75 rotor shaft and spindle disposed in said gear box.

4. The combination of a frame or body comprising a top body member provided with a handle and having a cylinder in its 80 under side and inlet and exhaust passages, an intermediate body member constituting a gear box, a bottom member, a valve for said inlet passage provided with a stem projecting above said handle, a fluid impact 85 rotor disposed in said cylinder, a rotor shaft projecting into said gear box, a spindle mounted on said bottom member, and a train of spindle driving gears connecting said 90 rotor shaft and spindle disposed in said gear box.

5. The combination of a frame or body comprising a top body member provided with a handle and having a cylinder in its under side and inlet and exhaust passages, 100 said inlet passage being provided with an annular delivery portion above the cylinder communicating with said cylinder through a plurality of ports, an intermediate body member constituting a gear box, a bottom 105 member, an upwardly facing fluid impact rotor disposed in said cylinder, a rotor shaft projecting into said gear box, a spindle mounted on said bottom member, and a train of spindle driving gears connecting said 110 rotor shaft and spindle disposed in said gear box.

6. The combination of a frame or body provided with a handle and a cylinder and a gear box disposed one above the other, an 115 inlet passage for said cylinder provided with an annular delivery portion communicating with said cylinder through a plurality of ports, a valve for said inlet passage provided with a stem projecting above said handle, 120 an upwardly facing fluid impact rotor disposed in said cylinder, a shaft therefor projecting into said gear box, a spindle disposed in alinement with said rotor shaft, a transmission shaft disposed at one side of said 125 rotor shaft and spindle, and a train of spindle driving gears on said rotor and transmission shafts and spindle.

7. The combination of a frame or body provided with a handle and a cylinder and 130

a gear box disposed one above the other, an inlet passage for said cylinder provided with an annular delivery portion communicating with said cylinder through a plurality of 5 ports, a valve for said inlet passage provided with a stem projecting above said handle, an upwardly facing fluid impact rotor disposed

in said cylinder, a shaft therefor projecting into said gear box, a spindle, and a train of spindle driving gears connecting said rotor 10 shaft and spindle disposed in said gear box.

In witness whereof I have hereunto set my hand and seal.

CORWILL JACKSON. [L. s.]
